UNITED STATES PATENT OFFICE.

PIERRE PEUGEOT AND GEORGE A. SHOEMAKER, OF CHICAGO, ILLINOIS,
ASSIGNORS TO BAKER-VAWTER COMPANY, OF CHICAGO, ILLINOIS,
A CORPORATION.

TEMPORARY BINDER.

SPECIFICATION forming part of Letters Patent No. 741,710, dated October 20, 1903.

Application filed January 30, 1902. Serial No. 91,867. (No model.)

To all whom it may concern:

Be it known that we, PIERRE PEUGEOT and GEORGE A. SHOEMAKER, both residents of the city of Chicago, county of Cook, in the State 5 of Illinois, have invented a certain new and useful Improvement in Temporary Binders, of which the following is a specification.

Our invention relates to that class of binders wherein one cover is removable for the 10 purpose of inserting and removing leaves, and more particularly to the locking mechanism of that class of devices designed to be manufactured in small and compact sizes, such as price-books, pocket-ledgers, and the like.

Our invention will fully appear in the following description, reference being had to the accompanying drawings.

In the drawings, Figure 1 represents a general view of the completed binder, showing it 20 filled with leaves and the lock engaged. Fig. 2 presents a cross-sectional view of Fig. 1, taken perpendicularly across narrow width of the binder and through the binding parts, showing in detail the locking mechanism.

Fig. 3 presents a particular and detailed view 25 of the locking mechanism engaged. Fig. 4 presents another detailed view of the locking mechanism, but released or disengaged. Fig. 5 presents a cross-sectional view of Fig. 1, 30 taken horizontally through the binding parts, and presents the locking mechanism in horizontal cross-section.

More particularly described, A represents the binder-body, consisting of covers a^1 , a^2 , 35 leaves a' , and binding-bars a^2 , a^2 .

B represents the locking-post, comprised of two parts B' and B^2 . Part B' consists of an oval-shaped tube b , one end of which is rigidly secured to one of the binding-bars a^2 , 40 preferably the lower one, and the other end projecting inward to engage with the other locking part B^2 , projecting inward from the opposite bar. In the center of and parallel with the tube b lies a threaded post b' , also rigidly secured at one end to the same binding-bar with which the tube b has engagement. This post b' extends as to its free and threaded end inwardly through the center of the tube b and to or approximately to the 45 same distance as the free end of the tube b . In corresponding position with the part B'

and telescoping with said part B' there extends from the other and opposite binding-bar the locking part B^2 . B^2 consists of an internally-threaded screw which passes through 55 an aperture in the said opposite binding-bar and registers and connects with the locking part B' . The construction of this screw B^2 is peculiar and demands particular description. The screw-shaft, which is an internally-threaded tube, is split in half from the threaded end to a point near the screw-head, forming the halves b^2 , b^2 . These halves b^2 , b^2 are so arranged that normally they stand apart at their threaded ends, as shown in Fig. 4, 60 but by pressure may be drawn together, as shown in Fig. 3. The screw-head b^3 is notched, b^4 , for operation as in ordinary screws. The screw part B^2 is arranged to pass through an aperture in one of the binding parts a^2 , a^2 , the 65 head b^3 holding the screw within the aperture and the halves b^2 , b^2 extending beyond the aperture and inwardly toward the part B' .

The operation of the lock is described as follows: The binding-bars a^2 , a^2 , the one presenting inwardly the tubular part B' and the other presenting inwardly the screw part B^2 , with the halves b^2 , b^2 sprung apart and the two parts B' and B^2 in corresponding position, 70 are brought together and the halves b^2 , b^2 fitted into the tube b in register with its largest diameter and encircling the threaded post b' , but lying free from contact therewith, as in Fig. 4. The screw part B^2 is then given a turn of ninety degrees and the halves b^2 , b^2 75 made to register with the shortest diameter of the tube b , as shown in Fig. 3 and in cross-section in Fig. 5. This operation draws the halves b^2 , b^2 together and engages the threads thereof with those of the post b' , thereby securing a firm connection of the parts B' and B^2 and locking the binder. Another quarter-turn of the screw registers the halves b^2 , b^2 80 with the longest diameter b and allows them to again spring apart, thereby releasing the 85 lock.

We purpose to use one or more of these lock-posts, as occasion may demand, and claim the right to secure the posts B' and B^2 permanently to the binding-bars or not, as may seem 90 most practicable.

As a variation of our invention the thread-

ed post b' may be done away with and the tube b be internally threaded and the halves $b^2 b^2$ externally threaded. Further, any suitable form of connection other than threads 5 may be used as seems desirable.

Any form of binding-posts may be used as desired. The form which we prefer and as illustrated, C-C, is the telescoping post described in United States Letters Patent No. 649,649, issued to Christian H. Stoelting, assignor to William A. Vawter, under date of May 15, 1900.

We claim as our invention—

1. A binder-lock consisting of parallel binding-bars together with an internally-threaded screw, the shaft of which is split, projecting inwardly through an aperture in one of the binding-bars, the head of which screw is larger than said aperture, and a corresponding oval-shaped tube secured to the opposite

binding-bar and projecting inwardly and a threaded post lying in the center of said tube and secured to the same binding-bar and projecting inwardly and parallel with said tube, substantially as described and for the purposes herein set forth. 25

2. A binder-lock consisting of an internally-threaded screw split the length of the shaft, the split parts of which normally lie apart and a corresponding tube of uneven diameter 30 fitted with a threaded post lying in its center and parallel with its length, the same having telescoping engagement with the said screw, substantially as described and for the purposes herein set forth.

PIERRE PEUGEOT.

GEORGE A. SHOEMAKER.
